UNITED STATES PATENT OFFICE

2,530,915

ROTARY IMPACT WRENCH DEVICE

Joseph Stee, Chicago, Ill.

Application December 29, 1947, Serial No. 794,379

2 Claims. (Cl. 81—52.3)

1

The present invention relates to impact wrenches and has for its main object the provision of an impact wrench of a comparatively simple construction, for use of removing or applying nuts to bolts by which wheels are mounted to the hub in a motor vehicle. Oftentimes it is impossible to remove nut from a bolt due to rust, unless an impact wrench is used.

A still further object of the present invention is the provision, in connection with an impact wrench of the character indicated, of a suitable device for holding the nut in a rigid stationary position while applying rotary movement to the bolt, in cases where the bolt has become disengaged from the hub. In such cases it is wholly impossible to disengage the nut from the bolt when the latter is not in a rigid stationary position.

With the above general objects in view and others that will appear as the invention is better understood, the same consists in the novel construction, combination and arrangement of parts hereinafter more fully described, illustrated in the accompanying drawings and pointed out in the appended claims.

In the drawings forming a part of this application, and in which like designating characters refer to corresponding parts throughout the several views:

Fig. 1 is an end elevational view of the present device;

Fig. 2 is a cross-sectional view thereof, taken on line 2—2 of Fig. 1;

Fig. 3 is a side elevational view of a nut engaging member employed with the present device;

Fig. 4 is an end elevational view of the said nut engaging member;

Fig. 5 is a top elevational view, partly in section, of the present device;

Fig. 6 is a longitudinal cross-sectional view through a nut engaging member, of another construction, with a bolt rotating member operable by the present device, for unscrewing the bolt from the nut in cases where the bolt has become disconnected from the hub, with means for maintaining said nut engaging member in a stationary position;

Fig. 7 is a perspective view of a handle for actuating the present device; and

Fig. 8 is a perspective view of the nut engaging member, last hereinabove mentioned.

Referring to the present drawings in detail, there is shown therein a frame, including four legs 10, which support a rectangular ledge 11.

2

Said legs are connected with supporting bars 12 and are strengthened by intermediate horizontal braces 13. Said ledge 11 defines central opening 14. The longer sides of said ledge 11 support a pair of bearings, generally indicated by 15 in Fig. 1, each of which includes base 16, which is rigidly affixed to ledge 11 by means of bolts 17. One of said bases 16 has an upright enlargement 18 at each end for supporting thereon, in an elevated position, a pair of tongues 19, which are pivoted upon bolts 17 for horizontal angular swinging movement.

Caps 20, affixed to bases 16, by means of bolts 21, and brasses 22, complete the structure of said bearings 15.

Receivable within each bearing 15, for rotary movement therewithin, is cylindrical shaft 23, each provided with a pair of spaced collars 24. Each pair of said collars 24 contacts the adjacent sides of each bearing 15, for preventing longitudinal movement of shafts 23 within bearings 15.

Integrally formed with one of said shafts 23, in a longitudinal relation therewith is a tool engaging extension 25 and impacting block engaging extension 26. Said extension 25 is disposed outwardly of the frame, while extension 26 is directed inwardly thereof.

Integrally formed with shaft 23 at the opposite bearing 15 is wrench tool engaging extension 27, disposed outwardly of the frame, and torque block engaging extension 28, the latter projecting from the opposite end of said shaft 23. Two shafts 23 and extensions 25, 26, 27 and 28 are in a longitudinal alignment. Said extensions 25, 26, 27 and 28 are square on a transverse cross-section.

Insertable upon extension 26 and frictionally held thereby is impacting block 29. Insertable upon extension 28, and held in like manner is torque block 30. Both said blocks 29 and 30 are of round formation, and at its center each is provided with a square opening for receiving their respective extensions 26 and 28, the latter being slightly tapered in a longitudinal direction in order that blocks 29 and 30 may be driven thereon and frictionally held in longitudinal relation with said extensions 26 and 28.

Integrally formed with block 29 and extending from its operative face is a pair of diametrically arranged ribs 31. Similar ribs 32 are provided at the operative face of torque block 30. When said blocks 29 and 30 are in an operative, face to face relation, as shown in Figs. 1, 5 and 6, the two

pairs of ribs 31 and 32 are in a staggered alternate relation, as shown in Fig. 2.

By virtue of the said arrangement the two pairs of ribs 31 and 32 have a clutch-like action, so that when a rotary movement is imparted to block 29, a rotary movement will be transmitted to block 30 by virtue of the interlocking of the two pairs of ribs 31 and 32. However, when block 29 is rotated no rotary movement is transmitted to block 30 until the two pairs of ribs 31 and 32 actually come in contact. During an interval of time prior to the two pairs of ribs 31 and 32 actually coming in contact it is possible to impart to ribs 31 an impacting motion for striking ribs 32 in order to impart to block 30 a forceful and sudden impact into a rotary direction, which in turn is transmitted to extension 27 which acts upon a nut to be unscrewed, and which action is considerably more forceful than the ordinary turning of a wrench. By virtue of the diametrical arrangement of the two pairs of ribs 31 and 32 and their mutual staggered relation, it is possible to impart to block 29 the impacting action substantially to 180 degrees.

Insertable upon wrench tool engaging extension 27 is wrench member 33 of a tubular formation, provided adjacent one of its ends with a square bore 34, within which said extension 27 is insertable. At the opposite end of said member 33 there is polygonal socket 35 whereby a nut to be unscrewed from a bolt is engaged.

To impart an impacting rotary action to block 29, suitable tool shown in Fig. 7, is provided. The same includes head 36 provided at its center with square bore 37 for engaging extension 25. A pair of bars 38, terminating with handles 39, laterally project from said head 36. Said bars 38 are in a longitudinal alinement. Upon inserting extension 25 within bore 37, manual angular swinging motion through handles 39 is imparted to bars 38 for imparting impacting rotary action to block 29 through shaft 23 and extensions 25 and 26, for the purpose hereinabove described.

It often happens that bolt 40 becomes disengaged from hub 41 contacting with felly 42. In such case it is a difficult matter to unscrew nut 43 from said bolt 40, because rotary movement imparted to nut 43 by ordinary means is transmitted to bolt 40, and the latter not being firmly and rigidly anchored within hub 41 or felly 42, thereby causing the rotation of both said bolt 40 and nut 43. By an attachment, presently described and operated by the impacting device, it is possible to support nut 43 in a rigid stationary position, while applying rotary movement to the square free end 44 of bolt 40.

The attachment aforesaid includes a tubular member 45, provided adjacent one of its ends with diametrically opposed slots 46. At the opposite end of said tubular member 45, and inwardly thereof there is polygonal socket 47 for receiving and engaging nut 43. When tongues 19 are shifted towards said tubular member 45 and brought into said slots 46, said tubular member 45 will be thereby locked to the frame of the impacting device, preventing said tubular member 45 to make any rotary shifting movement in either direction. This locks nut 43 to the impacting device, preventing said nut 43 from rotating in either direction.

Rod 48 is insertable within tubular member 45 in a concentric relation therewith. At one end said rod 48 has an integrally formed cylindrical extension 49, substantially corresponding in diameter to the inner diameter of said tubular

member 45. Said extension 49 snugly fits within said tubular member 45, but is permitted to make free rotary movement therewithin. Centrally and longitudinally of said extension 49 square bore 50 is made, within which extension 27 is insertable.

The opposite end of said rod 48 has a reduced, square extension 51 receivable within a corresponding bore made in cylindrical block 52. Ball 10 and socket connection 53 carried by said extension 51 maintain the latter in a frictional engagement with said cylindrical block 52 for preventing the latter and rod 48 to disengage during insertion of the two into said tubular member 45.

Made at the opposite end of said cylindrical block 52 is a polygonal central bore 54 for receiving and engaging the square end 44 of bolt 40.

By virtue of the construction of the said attachment hereinabove described and due to the engagement thereof with nut 43 and bolt 40, impacting rotary motion is imparted by block 29 to block 30. Said motion is transmitted to rod 48 due to the engagement of extension 27 therewith. Said motion is in turn transmitted by rod 48 to block 52, and the latter, due to its engagement with polygonal end 44 of bolt 40, transmits the same to said bolt 40. Thus, while nut 43 is gripped by tubular member 45 and thereby held keyed to the frame of the impacting device through the medium of tongues 19, bolt 40 receives impacting rotary motion, as hereinabove described, and is unscrewed from nut 43.

While there is described herein a preferred embodiment of the present invention, it is nevertheless to be understood that minor changes may be made therein without departing from the spirit and scope of the invention as claimed.

What I claim as new is:

40. 1. An impact wrench device for unscrewing nuts from bolts, comprising a pair of shafts supported in a longitudinally alined relation for rotary movement, a pair of blocks rigidly set upon the inner ends of said shafts in a face to face relation, ribs integrally formed on the adjacent faces of said blocks, the ribs in the two blocks being in an alternate mutual relation and shiftable upon a common plane in a transverse relation to said shafts, means for imparting a rotary movement to one of said shafts, and a nut engaging member carried by the other of said shafts, the rotary movement imparted to said first named shaft on operation of said means causing one of said blocks to make a rotary movement for impacting the ribs of said last named block against the ribs of the other of said blocks, the impacting force imparted to the last named ribs being transmitted to said second named shaft for effecting an impacted rotary movement in said nut engaging member.

2. An impact wrench device for unscrewing nuts from bolts, comprising a pair of shafts supported in a longitudinally alined relation for rotary movement, a pair of circular blocks each mounted upon the inner end of each shaft, said blocks being arranged in a face to face mutual relation, a plurality of radial ribs carried by the opposed faces of each of said blocks, the inner ends of said ribs in each of said blocks being in a spaced relation to the center of each block, the ribs of one block being in a staggered alternate relation with the ribs of the other of said blocks, the two groups of said ribs being arranged on a common plane transverse to said shafts so that when one of said blocks is rotated its ribs later-

ally engage the ribs in the other of said blocks in a clutchlike manner, means for imparting a rotary movement to one of said shafts, and a nut engaging member carried by the other of said shafts, the rotary movement imparted to said first named shaft on operation of said means being transmitted to one of said blocks for impacting the ribs carried thereby laterally against the ribs carried by the other of said blocks, the impacting force engendered by the impacting action of the ribs in the two blocks being transmitted to the second named shaft and said nut engaging member in a rotary torque for dislodging the engagement of the nut with the bolt.
